(57) **CLAIM**

The ornamental design for a sole, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a bottom view of a sole showing the claimed design;

FIG. 2 is a front view thereof;

FIG. 3 is a rear view thereof;

FIG. 4 is a left side view thereof;

FIG. 5 is a right side view thereof;

FIG. 6 is a top perspective view thereof;

FIG. 7 is a bottom view of a second embodiment of a sole showing the claimed design;

FIG. 8 is a front view thereof;

FIG. 9 is a rear view thereof;

FIG. 10 is a left side view thereof;

FIG. 11 is a right side view thereof; and,

FIG. 12 is a top perspective view thereof.

The dot-dash broken lines in the figures and the area(s) within the dot-dash broken lines show portions of the sole that form no part of the claimed design.

In the first embodiment, the different claimed colors create a contrasted appearance. In the second embodiment, the tonal variations represent areas with contrasting appearances.
